UNITED STATES PATENT OFFICE

LLEWELLYN M. CHRISTIE, OF PITTSBURGH, PENNSYLVANIA, ASSIGNOR TO NATIONAL FIREPROOFING CORPORATION, OF PITTSBURGH, PENNSYLVANIA, A CORPORATION OF PENNSYLVANIA

CONDUIT

Application filed June 18, 1930. Serial No. 462,053.

This invention relates to conduit, and more particularly to conduit adapted for housing cables or wires, pneumatic tube systems, underground pipe lines and the like. It relates still more particularly to a conduit of the type comprising a plurality of axially extending portions connected together in such manner that at least one of such portions may be removed to permit cables, wires and the like to be laid into the conduit, thus eliminating the necessity of drawing the same through.

Conduits of the type mentioned, generally known as "trough" conduits, are well known. An aim of the present invention is to improve such conduits by the provision of one in which the body or casing portion of the conduit and the top or cover portion are effectively secured or connected together, and also by the provision of means for effectively sealing the conduit so as to render it waterproof.

I provide a conduit comprising a plurality of axially extending portions connected together peripherally of the conduit, such portions being adapted to be interlocked, whereby to be positively held against outward displacement. I further provide a conduit comprising a hollowed casing member open at a portion of its periphery and a cover cooperating therewith for closing the open portion, the casing member and the cover being adapted to be interlocked whereby to be positively held against relative outward displacement.

In the accompanying drawings I have shown a present preferred embodiment of the invention, in which

Figure 1 is an isometric view of a length of conduit; and

Figure 2 is a cross-sectional view of the conduit shown in Figure 1.

Referring more particularly to the drawings, reference numeral 2 designates generally a body or casing member of a conduit which is formed of generally U-shape and provided with a cavity 3 adapted to receive cables, wires, tubes, pipes and the like. The bottom of the member 2 is generally flattened, as at 4, and the sides are flared somewhat out-

wardly near the top, as at 5, and each is provided internally of the member 2 with a seat or supporting portion 6 upon which is adapted to rest a top or cover 7.

The bottom of the cover 7 is substantially flat, as at 8, and is adapted to rest upon the oppositely disposed seat portions 6 of the member 2. The sides of the cover 7 are tapered downwardly and outwardly, as at 9, and the inner faces of the upper extremities 10 of the sides of the member 2 are similarly tapered, as at 10. The taper of the cover and body member are shown in the drawings to be substantially the same, although this is not essential.

After the cover has been put in place on the body or casing member of the conduit, sealing material such as cement 11 is adapted to be poured between the cover and the casing member. The sealing material not only seals the conduit and renders it substantially waterproof but also, by reason of the inclination of the lateral faces of the body member and cover, effectively wedges or keys the cover to the body whereby to tightly hold the cover in place and prevent the same from being lifted off.

As shown in the drawings, the width of the lower face of the cover 7 is very slightly less than the width of the top opening of the body member 2. This permits the cover to be put in place when the conduit is being assembled. It is not essential that the width of the cover be less than the width of the top opening of the body member because, on account of the taper of the upper extremities of the body member, the cover can be inserted by moving it angularly even though the width of the cover is substantially the same as the width of the top opening of the body member. By reason of the fact that the cover and body member are tapered as described, the cement or sealing material 11 poured in between the cover and body member serves upon hardening as a key or locking means to positively prevent removal of the cover. If it is attempted to remove the cover the sealing material will be compressed by a wedging action between the cover and the body member and will resist relative movement thereof. In

fact, it is not possible to lift out the cover without first breaking up the sealing material.

Although the invention is shown as applied to plane end conduit, it is equally applicable to bell and spigot conduit sections. When plane end conduit sections are used they are adapted to abut one another axially of the conduit, and in order to insure proper alignment, holes 12 for the reception of dowel pins are provided.

The body members of the respective conduit sections are adapted to be first laid in place as desired, whereupon the cables, wires, tubes, pipes or other devices may be laid in them. The necessity of drawing the cables or wires through the conduit is entirely eliminated. Furthermore, the conduit may be used for housing pipe lines by first laying the pipes in place and then pouring a waterproof compound or cement into the trough and around the pipes, thus, in effect, embedding the pipes in the cement or waterproof compound. The cover is laid in place and the sealing material 11 is poured in, thus completing the conduit.

Although it is desirable to use a sealing material such as cement for aiding in fastening together the cover and body member of the conduit, various other materials may be used, and, if desired, strips of suitable material such as rubber, fabric or the like may be inserted between the cover and body member to assist in or effect the desired seal and locking action. Preformed key means may be used in place of the cement 11, if desired, although it is more difficult to effect the sealing of the conduit when such means are utilized, particularly if a waterproof conduit is desired. The preformed keys serve equally as well as the poured cement to key the portions of the conduit together.

Preferably when the conduit is laid the trough members and cover members are staggered relatively to one another,—that is, each cover member extends across the joint between each pair of adjacent trough members. The respective trough members likewise extend across the joints between the respective cover members. Thus the respective component members of the conduit serve to strengthen the connections between the other component members. Even though dowel pins between adjacent trough sections should be omitted or become displaced, the cover member extending across the joint maintains the integrity of the conduit. This is true because of the key effect between the trough and cover members.

While I have shown and described a present preferred embodiment of the invention, it is to be understood that the same is not limited thereto but may be otherwise variously embodied within the scope of the following claims.

I claim:

1. A conduit comprising a trough portion providing a duct and having below its upper surface a pair of oppositely disposed substantially horizontal cover receiving surfaces, generally downwardly and outwardly and then generally upwardly extending surfaces into which said substantially horizontal cover receiving surfaces respectively merge, and a cover adapted to be seated upon said cover receiving surfaces. 70
75

2. A conduit comprising a trough portion providing a duct and having below its upper surface a pair of oppositely disposed cover receiving surfaces extending generally horizontally, then generally downwardly and outwardly, then generally upwardly and inwardly; and a tapered cover adapted to be positioned between said surfaces. 80

3. A conduit comprising a trough portion providing a duct and having below its upper surface a cover receiving recess the sides of which taper upwardly and inwardly, and a cover insertable into such recess by movement substantially in a plane perpendicular to the axis of the conduit, the sides of said cover when in place being adapted to be spaced from and lying generally parallel to the sides of the recess. 85
90

In testimony whereof I have hereunto set my hand.

LLEWELLYN M. CHRISTIE.
